TRAY TYPE LIQUID FUEL BURNER

Howard I. Piatt and Charles P. Thomas, Lansing,
Mich., assignors to Piatt Products Corporation,
Lansing, Mich., a corporation of Michigan

Application February 6, 1946, Serial No. 645,910

3 Claims. (Cl. 158—91)

1

The invention relates to burners for liquid fuel of the vaporizing pot type and has for one of its objects to provide an improved burner which is so constructed that it produces a clean flame throughout its range from low fire to high fire and may be manufactured at relatively low cost.

The invention has for other objects to provide a burner which is so constructed that both the primary air and the secondary air are preheated and to provide an improved burner comprising a shell which forms the pot and means within the shell for preheating both the primary air and the secondary air.

These and other objects of the invention will become apparent from the following description, taken in connection with the accompanying drawings, in which

Figure 1 is a plan view of a burner embodying the invention;

Figure 2 is a cross section on the line 2—2 of Figure 1;

Figure 3 is a view similar to Figure 2 showing a modified construction.

The burner for liquid fuel comprises the sheet metal shell 1 having a cylindrical side wall 2 and the integral bottom wall 3, which latter is preferably provided with the depressed pocket 4 adjacent a portion of the side wall. The burner also comprises the top wall or cover 5 which is preferably formed of sheet metal by a stamping operation and rests upon the upper end of the side wall 2 of the shell. This top wall or cover has the upright inner peripheral flange 6 forming a central opening and is provided with the annular series of peripherally spaced holes or openings 7 which are preferably formed during the stamping operation. 8 is a baffle extending transversely of the shell between the bottom wall and the top wall or cover and preferably supported upon the side wall of the shell. As shown, the lower portion 9 of the side wall is of less diameter than the upper portion 10 to form the internal annular shoulder 11 upon which the baffle rests. The baffle has the central outlet 12 and the outer peripheral bead 13 which forms an upwardly opening channel having the inner side wall 14, the bottom wall 15 and the outer side wall 16.

17 is an annular sheet metal wall in the nature of a cylinder fitting within the upright flange 6 of the top wall or cover and resting upon the baffle 8. This annular wall is provided with the annular series of peripherally spaced holes or openings 18 which are preferably elongated. 50

The baffle is also provided with the annular series of peripherally spaced holes or openings 19 which extend through the inner side wall 14 of the bead 13.

5 20 is a liquid fuel inlet tube fixed to the lower portion 9 of the side wall of the shell and registering with the pocket 4 and 21 is a lighter tube located above the liquid fuel inlet tube and closed during operation of the burner by the cap 22. 10 With the construction as above described, the annular wall 17 cooperates with the upper portion 10 of the side wall of the shell, the top wall or cover 5 and the baffle 8 to form an annular chamber for the preheating of the air which enters the chamber through the holes or openings 17. The holes or openings 18 in the annular wall provide for the passage of preheated secondary air from the chamber into the space or compartment formed by the annular wall and the combined area of these holes or openings is properly proportioned to the combined area of the holes or openings 7 to secure the required velocity of the preheated secondary air passing into the space or compartment. 15 The holes or openings 19 in the baffle 8 provide for the passage of preheated primary air laterally into the space or compartment below the baffle and the combined area of these holes or openings is proportioned to the combined area of the holes or openings 18 to secure the desired relative capacity for the primary air to assure efficient operation of the burner when at low fire through a range from pilot consumption to approximately one-quarter total capacity consumption. 20 The central outlet 12 in the baffle is of materially less diameter than the space or compartment encircled by the annular wall to assist in securing this result.

In the modification illustrated in Figure 3, the general construction is the same as that illustrated in Figures 1 and 2, with the exception that the primary air inlet holes or openings 23 and 24 are provided respectively in the side wall 25 and bottom wall 26 of the outer peripheral bead 27 of the baffle 28. Relatively few holes or openings, in the neighborhood of three, are provided in the bottom wall. With this construction, there is in addition to the primary air passing laterally into the space below the baffle a relatively small amount of primary air passing downwardly into the space below the baffle to mix with the liquid fuel or vapor and carry the same to the baffle outlet.

What we claim as our invention is:

1. A burner for liquid fuel comprising a shell having a side wall and a bottom wall, a top wall

3

for said shell having air inlet openings, a baffle spaced from said bottom and top walls and engaging said side wall, an annular wall cooperating with said side and top walls and said baffle to form an annular air chamber, said annular wall being formed with lateral openings intermediate its ends for the passage of secondary air from said chamber into the space encircled by said annular wall, said baffle being provided with a transverse wall having lateral openings providing for the passage of primary air from said chamber into the space below said baffle and also being provided with an outlet into and of smaller diameter than the space encircled by said annular wall, and means providing for the passage of liquid fuel into the space below said baffle.

2. A burner for liquid fuel comprising a shell having side and bottom walls, a top wall for said shell having air inlet openings, a baffle spaced from said bottom and top walls and having an outer peripheral upwardly opening bead engaging said side wall, an annular wall cooperating with said side and top walls and said baffle to form an annular chamber, said annular wall having lateral openings for the passage of secondary air from said chamber into the space encircled by said annular wall, said bead of said baffle having lateral openings for the passage of primary air from said chamber into the space below said baffle, said baffle having an outlet opening into the space encircled by said annular wall, and means providing for the passage of liquid fuel into the space below said baffle.

3. A burner for liquid fuel comprising a shell having side and bottom walls, a top wall for said shell,

5
10
15
shell, a baffle spaced from said bottom and top walls and engaging said side wall and having an annular upwardly opening bead, an annular wall cooperating with said side wall and top wall and baffle to form an annular chamber, said annular wall having lateral openings for the passage of secondary air from said chamber into the space encircled by said annular wall, said bead of said baffle having lateral openings for the passage of primary air from said chamber into the space below said baffle, said top wall and baffle each having an outlet opening in communication with the space encircled by said annular wall, means for placing said chamber in communication with the air outside the burner and means providing for the passage of liquid fuel into the space below said baffle.
